CYRIL AUBYN MASTERNAN, OF SURREY, ENGLAND, ASSIGNOR TO THE GAS LIGHT & COKE COMPANY, OF WESTMINSTER, LONDON, ENGLAND

REFRIGERATING SYSTEM

Application filed August 21, 1929, Serial No. 387,377, and in Great Britain September 1, 1928.

This invention relates to refrigerating systems. It involves the employment of the known type of refrigerating unit in which cold is produced by the rapid evaporation 5 of a liquid refrigerant, the vapour of which is absorbed by adsorbent or absorbing material. The liquid refrigerant is contained in an evaporating chamber and the adsorbent or absorbing material in a second chamber. 10 The two chambers are connected by a conduit and comprise a closed circuit for the vapour. The action of the unit is intermittent, the vapour being alternately adsorbed or absorbed by the material in said second chamber and then driven out of said material again and back into the evaporating chamber by the application of heat to the adsorbing or absorbing material. The vapour condenses on its way to or within the evaporating chamber. For the sake of brevity, the evaporating chamber will be referred to herein as the evaporator and the other chamber as the adsorber.

According to the present invention, a 25 refrigerating apparatus comprises in combination two refrigerating units of the type specified above, so arranged that the apparatus is adapted to operate continuously and automatically, while vapour is being expelled 30 from the adsorber and re-collects in liquid form in the evaporator of one unit, the reverse operation proceeding in the other unit.

The invention includes in a refrigerating apparatus of the above reversing adsorption 35 type, a pair of adsorbers and in connection with each adsorber, a boiler for generating vapour for heating the adsorber, a conduit for said vapour communicating with the boiler and in heat interchange relation to the 40 adsorbent material in the adsorber, and a reservoir communicating with the conduit and arranged to receive condensed vapour from it (or from a separate condenser situated between the conduit and the reservoir) 45 and deliver it, when a predetermined quantity has collected, to the boiler of the other adsorber.

Each adsorber in the arrangement specified in the preceding paragraph, may have 50 its own evaporator, the two evaporators

forming with their respective adsorbers separate closed circuits for the refrigerant vapour.

According to a feature of the invention, the evaporators may communicate with the 55 adsorbers by way of vapour conduits located adjacent one another and in heat interchange relationship. Similarly, the evaporators may be located adjacent to one another and in heat interchange relationship.

According to a further feature, the reservoirs are arranged to siphon-feed the boilers.

Preferably, in the arrangement aforesaid in which the reservoirs siphon-feed the boilers, the reservoirs deliver to auxiliary reservoirs which deliver in turn to the boilers, the rate of siphon-feed to the auxiliary reservoirs being such in relation to the normal rate of rise of liquid level in the reservoir, that the latter will empty faster than it fills. 70 By this means it is possible to provide a certain latitude for lack of symmetry as between the two units of the apparatus. In the case where the reservoirs siphon-feed the boilers directly, considerable precision and care have 75 to be exercised in the proportioning and construction of the two units, as it has to be ensured that make-of-siphon in one unit will coincide exactly with break-of-siphon in the opposite unit; otherwise a condition of perpetually dual-boiling tends to set up, that is to say, continual boiling in both units simultaneously, and this, of course, completely inhibits the operation of the apparatus.

The liquid refrigerant may be anhydrous 85 ammonia. According to a further feature of the invention, however, it may be an organic solvent such as butane, trimethylamine and the like. An advantage of the use of organic solvents is that it is possible to work 90 the apparatus at a lower pressure than when ammonia is the refrigerant. On the other hand, owing to latent heat considerations, a greater quantity of refrigerant has to be employed than in the case of ammonia.

The accompanying drawing illustrates diagrammatically one form of the invention.

The apparatus comprises two exactly similar units, A, B, each comprising an adsorber packed with active charcoal, an evaporator 100

containing anhydrous ammonia in liquid form, and a vapour conduit connecting the adsorber with the evaporator, so that the two are in hermetically sealed communication.

5 The adsorber, evaporator and conduit of unit A are marked 1, 2 and 3 respectively, and those of unit B 4, 5 and 6.

Each unit comprises, moreover, a boiler in the form of a spiral coil, for generating 10 steam for heating the adsorbent material

within the adsorber and thereby driving out the adsorbed vapour back into the evaporator, a steam coil within the adsorber and communicating with the boiler and a reservoir

15 voir for boiler water situated beneath the adsorber of the opposite unit and receiving condensed water from the steam coil within that adsorber. The boiler, steam coil and reservoir of unit A are marked 7, 8 and 9 respectively and those of unit B 10, 11 and 12.

The reservoirs 9 and 12 are provided with siphon-feed outlets 13, 14. These outlets lead into auxiliary reservoirs 15, 16 which are connected respectively to the boiler coils 25 7, 10 by conduits 17, 18. The reservoirs 15, 16 are of somewhat smaller dimensions than the main reservoirs 9, 12. The reservoirs 9, 12 are interconnected by a pressure-equalizing pipe 12a.

30 The boiler coils 7, 10 are intercalated and together form a cone-shaped enclosure 19 within which a gas flame 20 burns. The boilers and their heating means may, of course, take any other convenient form, if desired, and instead of a single heating means such as the flame 20, common to both boilers, each boiler may have its own independent heating means.

The action of the apparatus is as follows.

40 While the ammonia in evaporator 5 is being vaporized and the vapour therefrom is being adsorbed in the adsorber 4, adsorber 1 has heat imparted to it from steam condensing within the steam coil 8, and the ammonia

45 vapour being driven out from adsorber 1 is passing back to evaporator 2 where it collects in liquid form. On its way to evaporator 2 the vapour passes through the vertical portion 21 of the conduit 3, and in this

50 portion of the conduit it is cooled and its condensation is promoted. As soon as the adsorbent material in adsorber 4 has become saturated with ammonia vapour, the action of the apparatus is reversed and adsorber 4

55 becomes heated and adsorber 1 commences to take in vapour. The whole operation of the apparatus, including the reversal of action, is automatic, the quantity of boiler-water in the two units, and the rate of heat transferred to it from the flame 20, being suitably proportioned accordingly in relation to the speed of adsorption of the adsorbent material within the adsorbers.

60 The said portion 21 of the conduit 3 is cooled by cooling water circulating in the

cooling coil 22 surrounding the portions 21 of the conduits 3, 6. This cooling water, after circulating through the coil 22 passes to a second coil 23 surrounding adsorber 1. From this coil it passes on to a third coil 24 70 surrounding adsorber 4 and thence away.

The evaporators 2, 5 are, of course, located within the chamber 25 to be refrigerated, and the portions 21 of the conduit 3, 6 are located outside of said chamber. 75

The said portions 21 of the conduits 3, 6 are adjacent one another, as shown, so as to be in heat-interchange, relationship, and they are fitted internally with horizontal baffles 26 which serve further to promote condensation 80 of the vapour passing to the evaporators.

Instead of the cooling-water coil 22 the portions 21 of the conduits 3, 6, which, as will be appreciated, constitute condensers for 85 the ammonia vapour, may be fitted exteriorly with air-cooling fins.

The cooling-water coils 23, 24 are for the purpose of cooling the adsorbers and thereby increasing the efficiency of the adsorbent 90 material therein.

The steam pipes connecting the two boiler coils 7, 10 with the steam coils 8, 11 are preferably lagged to conserve the heat of the steam.

It will be appreciated that the siphons 13, 14 operate to empty the emptying reservoir faster than the filling reservoir fills, and their dimensions are chosen accordingly. 95

One of the reservoirs, say the reservoir 9, is preferably provided with an additional 100 outlet 27 leading to the auxiliary reservoir 15 and controlled by a stop cock 28. This additional outlet 27 is to facilitate the operation of starting of the apparatus.

The closed system provided in each unit 105 by the boiler coil, the steam coil and the reservoir contains, in addition to water, an inert gas such as nitrogen. The requisite quantities of water and gas are, of course, predetermined by trial to afford the automatic action, aforesaid, of the apparatus. It is obvious that, instead of water, any other suitable liquid may be employed in the heating system. 110

If desired, the adsorbers may be heated electrically, a thermostatic control switch providing automatic operation of the heating system. 115

In order to ensure maximum efficiency of 120 operation, care should be taken in the proportioning of the contents of the adsorbers. The thickness of charcoal or other adsorbent surrounding the heating coil, that is to say, the thickness of charcoal between the heating coil and the exterior walls of the adsorber, should be such that the heat transferred through it per hour is equivalent to the heat involved in condensing the liquid component in the charcoal in the same period of time. 125 This will be readily appreciated from what 120

follows. During the heating phase of the cycle, a certain quantity of heat will be required to be transferred through the body of charcoal from the central heating coil outwardly to the exterior wall of the adsorber, and during the cooling period which follows, that is to say, the period during which ammonia is passing back into the adsorber, the same amount of heat will require to be dissipated. The ammonia, however, coming over from the evaporator will first be adsorbed by the outer layer of charcoal, which will be the coolest layer, and adsorption will penetrate steadily inwards towards the heating coil. The inverse, of course, takes place in the adsorbent-regenerating phase of the cycle, the ammonia becoming driven off first from the interior charcoal layers nearest the heating coil and the regenerating effect progressing steadily outwards. The rate of adsorption will be largely controlled by the heat dissipation, a large factor in which, especially in the later stages of the adsorption phase, is, of course, the conductivity and thickness of the charcoal layers. Too rapid dissipation of heat will lead to the completion of the adsorption phase before the heating period on the opposite side of the plant is completed and conversely too slow dissipation of heat will lead to incomplete adsorption and, in consequence, a reduction of cooling effect in the refrigerating chamber.

I claim:

1. In a refrigerating apparatus of the reversing adsorption type, a pair of adsorbers and in connection with each adsorber, a boiler for generating vapour for heating the adsorber, a conduit for said vapour communicating with the boiler and in heat-interchange relation to the adsorbent material in the adsorber, a reservoir communicating with the conduit and arranged to receive condensed vapour from it and means communicating with the reservoir and with the boiler of the other adsorber and adapted when a predetermined quantity of vapour condensate has collected in the reservoir to deliver it to the last mentioned boiler.

2. In a refrigerating apparatus of the reversing adsorption type, a pair of adsorbers, a corresponding pair of evaporators allocated respectively to the adsorbers, conduit means placing each adsorber into sealed communication with its evaporator and in connection with each adsorber, a boiler for generating vapour for heating the adsorber, a conduit for said vapour communicating with the boiler and in heat-interchange relation to the adsorbent material in the adsorber, a reservoir communicating with the conduit and arranged to receive condensed vapour from it and means communicating with the reservoir and with the boiler of the other adsorber and adapted when a predetermined quantity of vapour condensate has collected

in the reservoir to deliver it to the last mentioned boiler.

3. A refrigerating apparatus according to claim 2, wherein the evaporators are located adjacent to one another and in heat-interchange relationship.

4. In a refrigerating apparatus of the reversing adsorption type, a pair of adsorbers and in connection with each adsorber, a boiler for generating vapour for heating the adsorber, a conduit for said vapour communicating with the boiler and in heat-interchange relation to the adsorbent material in the adsorber, a reservoir communicating with the conduit and arranged to receive condensed vapour from it and siphon means communicating with the reservoir and with the boiler of the other adsorber and adapted when a predetermined quantity of vapour condensate has collected in the reservoir to deliver it to the last mentioned boiler.

5. In a refrigerating apparatus of the reversing adsorption type, a pair of adsorbers and in connection with each adsorber, a boiler for generating vapour for heating the adsorber, a conduit for said vapour communicating with the boiler and in heat-interchange relation to the adsorbent material in the adsorber, a reservoir communicating with the conduit and arranged to receive condensed vapour from it, a second reservoir in communication with the boiler of the other adsorber and a siphon placing said second reservoir into siphon-feed communication with the first reservoir so that when a predetermined quantity of vapour condensate has collected in the first reservoir said quantity is delivered to the second reservoir and thereby to the boiler of said other adsorber, the rate of siphon-feed being such in relation to the normal rate of rise of liquid-level in the reservoir, that the reservoir will empty faster than it fills, for the purpose specified.

6. A refrigerating apparatus according to claim 1, wherein the adsorber-heating conduits take the form of spiral tubes, the vapour from the boilers entering these tubes at the top and the condensate leaving them at the bottom.

7. A refrigerating apparatus according to claim 1, wherein the boilers take the form of spiral pipe coils situated adjacent one another so as to be heated by a single heating means common to them both.

8. In refrigerating apparatus, a plurality of generators, means for heating said generators, and stationary means within said heating means for discontinuing the heating of one of said generators and starting the heating of a second of said generators.

9. Refrigerating apparatus including a plurality of generator-absorbers, a closed circuit containing a heating fluid for each generator-absorber, each closed circuit including a condensing portion in heat exchange re-

lation with the generator-absorber, a liquid collecting portion, and a vaporizing portion, and siphon means for transferring the liquid collected in said collecting portion of one of said circuits after a predetermined amount of liquid has collected in said liquid collecting portion.

In testimony whereof I have signed my name to this specification.
